US0D1044362S

(12) **United States Design Patent** (10) **Patent No.:** **US D1,044,362 S**
(45) **Date of Patent:** **** Oct. 1, 2024**

(54) **UNDER-SHELF STORAGE**

(71) Applicant: **FREE-FREE INDUSTRIAL CORP,**
Taipei (TW)

(72) Inventor: **Sheng-Yu Liu**, Taipei (TW)

(73) Assignee: **FREE-FREE INDUSTRIAL CORP,**
Taipei (TW)

(**) Term: **15 Years**

(21) Appl. No.: **29/801,200**

(22) Filed: **Jul. 28, 2021**

(30) **Foreign Application Priority Data**

Feb. 9, 2021 (TW) 110300797

(57) **CLAIM**

The ornamental design for an under-shelf storage, as shown
and described.

DESCRIPTION

FIG. 1 is a perspective view of an under-shelf storage
showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is second perspective view.

The broken lines in the drawings illustrate portions of the
under-shelf storage that form no part of the claimed design.

1 Claim, 8 Drawing Sheets
